UNITED STATES PATENT OFFICE.

MARCELLUS W. MEEK, OF CHICAGO, ILLINOIS.

RACK.

1,333,930.

Specification of Letters Patent. Patented Mar. 16, 1920.

Application filed July 26, 1919. Serial No. 313,454.

To all whom it may concern:

Be it known that I, MARCELLUS W. MEEK, a citizen of the United States, residing at Chicago, in the county of Cook and State 5 of Illinois, have invented certain new and useful Improvements in Racks, of which the following is a specification.

This invention relates to a light rack for retaining hay, fodder, or eatables of any 10 kind such as are particularly suitable for small animals—rabbits, for instance.

I have aimed in the present device to produce a structure that is essentially simple, light, and easy to manufacture; one 15 that may be easily transported and mounted for use; and one that is so formed as to retain its intended contents while at the same time rendering it easy to obtain access thereto.

With these objects in view, the description 20 of this invention will now be given, reference being made to the accompanying drawing wherein a suggested structure is shown in perspective.

It will be found convenient to form the 25 present rack out of wire possessing a suitable strength and stiffness, and in its fabrication a section of wire designated as A is bent in the form shown to provide a front 30 upper rail 1 and end rails 2 each turned at its extremity by preference in the form of an eye 3 through which may be inserted a nail or screw to fasten the device in place. It may be stated that a rack of this kind is 35 most commonly hung upon a vertical support such as the wall 5 which is illustrated for convenience, this wall constituting a rear side or back for the rack. The elevation 40 of the rack upon the wall will, of course, be chosen with reference to the convenience of the animals for which it is intended.

A second section of wire designated as 45 B is likewise bent to provide a lower rail 6 of substantially the same length as the upper rail 1, the wire at each end of the rail 6 making a three-fourths turn (about 270 degrees) so as to form end rails 7 which in the structure as used are disposed in a 50 direction inclined at an angle less than 45° from the vertical, as distinguished from the end rails 2 which lie in a plane inclined at an angle less than 45° from the horizontal. In making the three-fourths turn noted, 55 the section B forms at each end of the rail 6 an eye 8 through which a fastening de-

vice 9 (such as a nail or screw) may be driven to secure the rack along its bottom adjacent the wall 5. The upper extremities of the end rails 7 are each joined to the rails 60 2 at a convenient point 10, say midway of their length, by any suitable means such, for instance, as solder. Other rails 11 may also be extended between and fastened to the upper and lower rails 1 and 6, these 65 rails 11 being spaced apart at any distance that is found suitable for retaining the contents of the rack in a manner that permits easy extraction thereof.

The rack formed as herein described may 70 be readily attached in place. When employed in the manner described, its front side composed in part of the rails 11 will be obliquely inclined in such a way as to provide in effect a V-shaped pocket whose 75 ends are defined by the rails 7. The hay or other eatables placed in the rack will accordingly be accessible from the front and ends as well as the top of the device.

The various features that characterize 80 this rack—its lightness, its openness, and simplicity—impart to the structure certain advantages that are not possessed by other devices of this general kind with which I am aware, and for which I hereby make 85 claims as follows.

I claim:

1. A rack of the kind described comprising a wire bent to provide an upper rail having a front and end portions in angular 90 relation thereto, the extremity of each end portion being turned to lie substantially parallel with the front and formed to provide an eye, a lower rail having two bends, each of about 270 degrees, to provide an 95 eye, the portions beyond such bends constituting end rails and being extended to connect with the end portions of the upper rails, and a plurality of rails connecting the upper and lower rails on the front side of 100 the rack, the eyes in the device adapting it for attachment to a wall by which it is provided with a rear side, substantially as described.

2. A rack of the kind described comprising 105 a wire bent to provide an upper rail having a front and end portions in angular relation thereto, the extremity of each end portion being formed to provide an eye through which an element may pass to make 110 fastening with the wall, a lower rail having two bends each arranged to provide an

eye, the portions beyond such bends constituting end rails and being extended to connect with the end portions of the upper rail, the eyes in the lower rail being adapted to receive therethrough an element which makes fastening to a wall, and a plurality of rails connecting the upper and lower rails on the front side of the rack, the wall rear-

wardly of the device and the front side thereof being in angular relation to provide 10 in effect a V-shaped pocket, substantially as described.

MARCELLUS W. MEEK.
